UNITED STATES PATENT OFFICE.

OSCAR MUSSINAN, OF NEW YORK, N. Y.

PIN TICKET OR TAG.

SPECIFICATION forming part of Letters Patent No. 639,083, dated December 12, 1899.

Application filed August 10, 1899. Serial No. 726,829. (No model.)

To all whom it may concern:

Be it known that I, OSCAR MUSSINAN, a citizen of the United States, residing at New York, in the county and State of New York, 5 have invented certain new and useful Improvements in Pin Tickets or Tags, of which the following is a specification.

My invention has for its object to improve the construction of pin tickets or tags generally used for applying distinguishing marks, numbers, or prices to merchandise, such as garments, fabrics, and the like; and my invention consists in a pin ticket or tag provided with a staple-shaped fastening-pin bent 15 and applied in a manner hereinafter explained to stiffen and support the tag and so that the pointed prongs or shanks will extend outwardly from the upper edge of the tag and in the plane of its face instead of at right angles 20 thereto, as usual, thereby enabling the tag to be more conveniently inserted and removed and rendering it more compact for packing and easier to write or print upon before affixing it to the goods.

25 In the accompanying drawings, Figure 1 is an enlarged plan view of a pin ticket or tag embodying my invention. Fig. 2 is a perspective view of the reverse or under side of the same. Fig. 3 is a longitudinal vertical 30 section of the same on the line 3 3 of Fig. 1. Fig. 4 is an enlarged perspective view of the fastening-staple detached from the tag or ticket. Fig. 5 is an inverted view of the fastening-staple or wire partially bent and ready 35 to be applied to the tag.

In the drawings, A represents a ticket or tag which may be composed of cardboard, thick paper, or other suitable material and of any desired shape and size to receive the distinguishing marks, numbers, or characters which it may be desired to apply to the goods, articles, or material on which the tag is to be used.

B is the fastening pin or staple, which is 45 composed of a single piece of wire bent into a U shape and having its doubled end bent at a a' and b b' at right angles, as shown in Fig. 5, before being applied to the tag.

c c are the prongs or pointed shanks which 50 engage with the goods or fabric when the tag is to be attached thereto.

In attaching the fastening-staple B to the

ticket or tag the pointed prongs c c are first passed through the same from the front side until the two portions 10 10 lie flat upon its 55 upper surface, with the loop d extending down over and in contact with its edge 12. The loop d is then bent inwardly at a right angle and clenched down upon the under surface of the tag, as shown in Fig. 2, firmly embracing the edge 12, after which the prongs c c are bent down upon said under surface, so as to project outwardly from the upper edge 12 of the ticket in the plane of its face, the clenched-down loop or return-bend d lying 60 between the two prongs c c, as shown in Fig. 2. The wire thus bent is securely and immovably fastened in place and serves to firmly clamp and support the upper portion of the tag, while in the operation of inserting and removing 65 the tag the pressure and strain are exerted in the plane of its face instead of in a direction at right angles thereto, as heretofore, thereby lessening the liability of bending or breaking the tag and facilitating the 70 operation of affixing the same to the goods, as the ticket can be conveniently grasped between the finger and thumb without liability of coming into contact with the sharp points of the prongs. Furthermore, the extension 75 of the prongs in the plane of the face of the ticket or tag instead of projecting at right angles from its lower face, as heretofore, renders it much more compact and much easier to pack into boxes in large quantities, while 80 as it will lie flat on a table or other surface it can be much more easily marked, written upon, or printed before being attached to the goods. Another advantage is that in removing 85 the ticket from a quantity in a box or package there is very little liability of the fingers being pricked or injured by contact with the ends of the prongs.

A most valuable result follows the actual use of my improved ticket or tag upon the 90 goods—viz., the ticket or tag becomes a protector for the points of the prongs or pins. This is due to the fact that in applying the ticket the pins or prongs are passed through the goods and out through the face thereof, 95 after which the prongs or pins are bent laterally until they lie between the goods and the rear face of the ticket or tag. As thus concealed behind the ticket, the prongs or

pins will be prevented from pricking the person handling or trying on the goods—hosiery, for instance—and the pins will be prevented from catching in other goods and tearing the 5 same.

What I claim as my invention, and desire to secure by Letters Patent, is—

1. As an improved article of manufacture, a pin tag or ticket provided with rigidly-connected, flexible penetrating prongs or pins projecting in or approximately in the direction of the plane of the tag or ticket, whereby the pins may be passed through the goods and out on the same side thereof and then bent down 15 under the tag or ticket for protection thereby.

2. A pin ticket or tag, provided with a staple-shaped fastening-pin having its prongs or

shanks passed through the ticket from the front side or face thereof, contiguous to its edge and having its loop or doubled end lying close against the front face of the ticket and turned over its edge, and thence bent inwardly and clenched down upon the under face of the ticket so as to lie between the prongs, said prongs being bent down upon 20 said under face and projecting outwardly from the upper edge or top of the ticket in the plane of its face, substantially as described.

Witness my hand this 4th day of August, A. D. 1899.

OSCAR MUSSINAN.

In presence of—

P. E. TESCHEMACHER,
LILLIAN I. BASFORD.
